CLAIM

The ornamental design for a kickplate extender, as shown and described.

DESCRIPTION

FIG. 1 is a front perspective view of a kickplate extender, with a pair of screw holes shown in broken lines.

FIG. 2 is a rear elevation view thereof.

FIG. 3 is a front elevation view thereof.

FIG. 4 is a side elevation view thereof.

FIG. 5 is a side elevation view thereof.

FIG. 6 is a top plan view thereof.

FIG. 7 is a bottom plan view thereof; and,

FIG. 8 is a front perspective view thereof, showing a wire running down a furring strip and across the kickplate extender, the wire and furring strip shown in broken lines. The subject matter delineated in broken lines, showing wires, furring strips, outlets, and screw holes, illustrates environment and forms no part of the claimed design.
